ELECTRIC IRON

Walter E. Belcher, Seattle, Wash.

Application August 24, 1934, Serial No. 741,316

5 Claims. (Cl. 219—25)

My invention relates generally to electric irons, and particularly to an electric iron embodying novel gravity and thermostatically controlled switching means for controlling the energization 5 and deenergization of the electrical heating element thereof, and an important object of the invention is to provide simplified and efficient control means of the character indicated which is inexpensive and rugged and efficient in operation.

It is also an important object of my invention to provide control means of the character described above which is capable of being incorporated in an ordinary electric iron without extensive alterations thereto.

It is also an important object of my invention to provide control means of the character indicated above which is also applicable to other tools and appliances for controlling the energization 20 thereof while in use and while not in use.

Other objects and advantages of my invention will be apparent from a reading of the following description in connection with the drawings, wherein for purposes of illustration I have shown 25 a preferred embodiment of my invention.

In the drawings:—

Figure 1 is a longitudinal vertical sectional view through an embodiment of the invention as applied to a sadiron.

30 Figure 2 is a longitudinal sectional view through the embodiment showing the embodiment in the position in which it is placed when not in use.

Figure 3 is a sectional view similar to Figure 2 showing the control in operated condition.

35 Figure 4 is a transverse vertical sectional view taken through Figure 1 approximately on the line 4—4.

Figure 5 is a top plan view of the stationary plate.

40 Figure 6 is a transverse vertical sectional view taken through the temperature control stop approximately on the line 6—6 of Figure 1.

Figure 7 is a top plan view of the contact arms on the swingable arm.

45 Referring in detail to the drawings, the numeral 5 refers generally to a conventional type of sadiron casing on which is mounted the handle 6, the handle in this instance being provided in its underside with a longitudinal slot 7 cut in a vertical plane and having across one end a pivot 8 on which is pivoted one end of a gravity affected lever 9 which has in its opposite end a screw or bolt 10 providing loose anchorage for the upper end of a link 11 which has a hole loosely receiving the shank portion of the screw 10 and has its opposite end depending through an opening 12 in the rear portion of the top of the casing 5 and through a transverse slot 13 in the stationary plate 14, the lower end of the link 11 having itself an opening through which is en-

gaged the rear end of the bi-metallic heat affected arm 15.

Located in the top of the casing 5 is a spheroidal bushing 16 in which is threaded a stop 17 having a turning lever 18 on its upper end, the lower end 19 of the stop passing through an opening 20 in the stationary plate 14 in a position to be contacted by the bi-metallic arm 15 as shown in Figure 3.

The stationary plate 14 is elongated and generally rectangular in form as shown in Figure 5 and has an opening 20 through which passes the anchorage post 22 by means of which the plate 14 is stationarily supported in a horizontal position shown in Figure 1. The front end of the 15 plate has a depending flange 23 which acts as a limit stop for the swingable arm 24, and the sides of the front end of the plate 14 have depending ears 25, 26 through which passes a pivot 27 which also passes through upstanding ears 20 28 on the swingable arm 24, so as to pivotally support the swingable arm 24 for movement in a vertical plane. The stop flange 23 on the stationary plate limits the downward swinging of the rear end of the arm 24 to approximately the 25 horizontal as shown in Figure 1. The swingable arm has an opening 29 whose edges are spaced from and around the anchorage post 22 to permit free movement of the arm 24. The rear end of the stationary plate 14 has thereon the usual 30 terminals 30, 31 projecting through suitable bushings 32, 33, respectively, in the rear part of the casing for connection of the usual cable or cord for energizing the iron, and the rear end of the casing is provided with an angular rest 35 34 enabling standing the iron upon its heel in the position shown in Figure 2.

The swingable arm 24 has a downwardly declining portion 35 on which is mounted in an insulated manner a heavy weight 36 below the 40 part 35 and above the part 35 there is connected in an insulated manner the spring contact arms 37, 38, respectively, having the respective contacts 39, 40 for engaging with the leads 41 from the terminals 42 of the electrical heating 45 element (not shown), the leads 41 being flexible.

When the iron is in the position shown in Figure 1 the weight 36 holds the arm 24 in the depressed horizontal position shown in this figure, so that the link 11 holds the lever 9 in the downwardly angulated position shown. When, however, the iron is set up on its heel as shown in Figures 2 and 3, the force of gravity alone on the weight 36 will cause the arm 24 to move toward the right, that is, toward the stationary plate 14, 50 with the result that the contacts 39, 40 will engage the terminals 30, 31 and thereby energize the heating element of the iron until such a temperature of the iron has been reached that the bi-metallic arm 15 starts to curve until it has curved 55 60

to a position exemplified in Figure 3, wherein the bi-metallic arm has contacted the stop 17 and pushing thereagainst has caused the contacts 39, 40 to disengage from the terminals 38 and 34, 5 thereby breaking the circuit to the heating element of the arm.

It is obvious that the stop 17 may be adjusted so that the bi-metallic arm 15 will operatively engage the bi-metallic arm in the circumstances 10 described, so that the current may be automatically shut off in the manner indicated at any desired temperature.

Although I have shown and described herein a preferred embodiment of my invention, it is to 15 be definitely understood that I do not desire to limit the application of the invention thereto, and any change or changes may be made in the materials and in the structure and arrangement of parts, within the spirit of the invention and the 20 scope of the subjoined claims.

What is claimed is:—

1. An electric iron of the character described comprising a casing having a handle, said casing containing an electrical heating element, 25 electric terminals mounted on the casing and having each a portion within the casing, a lever pivoted on the handle and having a link depending into the casing, a swingable arm pivoted within the casing and containing contacts connected to the heating element, a bi-metallic arm on the last-mentioned arm and connected to said link, said lever, said link, and said swingable arm being adapted to swing gravitationally to a position other than the initial position thereof when 30 the iron is tilted and placed on its heel, contacts on the swingable arm engageable with said terminals and energizing the heating element, an adjustable stop on the casing, said bi-metallic arm being adapted to curve at a predetermined 35 temperature so as to engage and work against said stop in a manner to push the contacts away from said terminals and deenergize the heating element.

2. An electric iron of the character described 45 comprising a casing having a handle, said casing containing an electrical heating element, electric terminals mounted on the casing and having each a portion within the casing, a lever pivoted on the handle and having a link depending into the casing, a swingable arm pivoted within the casing and containing contacts connected to the heating 50 element, a bi-metallic arm on the last-mentioned arm and connected to said link, said lever, said link, and said swingable arm being adapted to swing gravitationally to a position other than the initial position thereof when the iron is tilted and placed on its heel, contacts on the swingable arm engageable with said terminals and energizing the heating element, an adjustable 55 stop on the casing, said bi-metallic arm being adapted to curve at a predetermined temperature so as to engage and work against said stop in a manner to push the contacts away from said terminals and deenergize the heating element, said adjustable stop being mounted on the top of the casing.

3. An electric iron of the character described 70 comprising a casing having a handle, said casing containing an electrical heating element, electric terminals mounted on the casing and having each a portion within the casing, a lever pivoted on the handle and having a link depending into the casing, a swingable arm pivoted within the cas-

ing and containing contacts connected to the heating element, a bi-metallic arm on the last-mentioned arm and connected to said link, said lever, said link, and said swingable arm being adapted to swing gravitationally to positions other than the initial positions thereof when the iron is tilted and placed on its heel, contacts on the swingable arm engageable with said terminals and energizing the heating element, an adjustable stop on the casing, said bi-metallic arm being adapted to curve at a predetermined temperature so as to engage and work against said stop in a manner to push the contacts away from said terminals and deenergize the heating element, said adjustable stop being mounted on the top of the casing, and manual means for adjusting said stop exposed on the exterior of said casing.

4. An electric iron of the character described comprising a casing having a handle, said casing containing an electrical heating element, electric terminals mounted on the casing and having each a portion within the casing, a lever pivoted on the handle and having a link depending into the casing, a swingable arm pivoted within the casing and containing contacts connected to the heating element, a bi-metallic arm on the last-mentioned arm and connected to said link, said lever, said link, and said swingable arm being adapted to swing gravitationally to positions other than the initial positions thereof when the iron is tilted and placed on its heel, contacts on the swingable arm adjustable with said terminals and energizing the heating element, an adjustable stop on the casing, said bi-metallic arm being adapted to curve at a predetermined temperature so as to engage and work against said stop in a manner to push the contacts away from said terminals and deenergize the heating element, said lever being operable into a slot provided in the handle by grasping the handle, for engaging said contacts and said terminals for energizing the iron while in use.

5. An electric iron of the character described comprising a casing having a handle, said casing containing an electrical heating element, electric terminals mounted on the casing and having each a portion within the casing, a lever pivoted on the handle and having a link depending into the casing, a swingable arm pivoted within the casing and containing contacts connected to the heating element, a bi-metallic arm on the last-mentioned arm and connected to said link, said lever, said link, and said swingable arm being adapted to swing gravitationally to positions other than the initial positions thereof when the iron is tilted and placed on its heel, contacts on the swingable arm engageable with said terminals and energizing the heating element, an adjustable stop on the casing, said bi-metallic arm being adapted to curve at a predetermined temperature so as to engage and work against said stop in a manner to push the contacts away from said terminals and deenergize the heating element, said lever being operable into a slot provided in the handle by grasping the handle, for engaging said contacts and said terminals for energizing the iron while in use, said swingable arm, said link and said lever being adapted to fall when not supported with the hand so as to disconnect the contacts from the terminals and deenergize the heating element of the iron.

WALTER E. BELCHER.
